UNITED STATES PATENT OFFICE

LYMAN D. JONES, OF NEW YORK, N. Y.

TOBACCO-SMOKING APPLIANCE

Application filed May 5, 1928. Serial No. 275,481.

This invention relates to a tobacco smoking appliance or outfit which in a way is comparable with the Turkish hookah or the Persian nargile, mainly intended for the 5 smoking of pipe tobacco, although it may be used in the smoking of cigarettes or cigars.

One of the objects of the invention is to provide a comparatively large chamber constituting a holder for absorbent material, 10 such as a sponge for example, the same being provided with a wide mouthed open neck, of ample size, to permit the introduction of the wet material or sponge readily into the holder, and for permitting the ready removal of 15 the material or sponge for the purpose of cleansing it. Furthermore, the wide mouthed open neck permits the easy pouring of water therethrough and onto the sponge or the like without danger of spilling the water 20 onto the outside of the holder, etc., such pouring being accomplished with the neck of the holder directed upwardly, the holder then being inverted and attached to the supporting base of the holder. Preferably the 25 supporting base is ponderous so as to support the holder and the remainder of the appliance without danger of the appliance becoming upset when it is in use or otherwise. Other advantages and objects will be apparent from the specification.

With these objects in view, the invention consists of certain features of construction and combinations of parts, to be hereinafter described and then claimed with reference to 30 the accompanying drawings illustrating a preferred embodiment of the invention, in which:

Figure 1 is a longitudinal sectional view of the appliance, parts being in elevation and 40 in broken lines, and

Fig. 2 is a plan of the appliance on a reduced scale, the tubing for the mouth-piece being broken away.

Referring to the drawings, the supporting 45 base 10 is preferably circular and may be composed of metal, glass or other suitably heavy material so as to support the appliance without danger of its tipping over. The base 10 is preferably provided with a cavity 50 11 so as to somewhat lighten it and at the

same time enable it to more properly rest upon a table or other support. The cavity 11 is closed by a sheet metal or other disk 12 and is faced by a soft sheet 13 of felt or the like which may be adhesively secured to the 55 lower edge of the base so as to provide means to avoid the defacing of the surface of a table or other piece of furniture, and to tend to prevent the slipping of the device.

A hollow holder 14 is provided, having a 60 wide mouthed open neck 15 such neck approaching the interior diameter of the holder but being preferably slightly less than such diameter. When the appliance or device is set up the said neck 15 extends downwardly 65 it being screw threaded to engage with a corresponding screw thread on the inner wall of a conical portion 16 of the base, which provides a shallow cylindrical recess for receiving the said neck. The neck 15 is of a 70 length slightly less than the length of the conical portion 16, so that its lower edge is spaced slightly away from the bottom of the cylindrical recess, whereby to admit the introduction of a packing disk or washer 17 75 between the lower edge of the neck and the bottom of the recess. The packing disk is substantially flat and preferably covers the bottom of the said recess. When the neck is screwed as far in as possible, the packing 80 is slightly compressed and seals the joint at the place where it is located, thereby to prevent the exudence of water or moisture through the joint, thus maintaining the outer surface of the base 10 in a neat and dry condition. When the disk extends over and covers the bottom of the recess of base 10 it excludes moisture from the base especially if the base be made of wood or other porous 85 material.

Within the preferably spherical holder 14 there is received absorbent material 18 which may consist of a sponge, the same being saturated with water so as to cool the smoke, and remove some of the objectionable qualities of the tobacco. As the neck 15 has a wide mouth, the sponge 18 or the like may be readily removed, upon unscrewing the holder from the base 10, so that the sponge or the like may be cleansed and again saturated 90 95 100

with water. Or, when the holder is removed and the sponge or the like replaced therein, it may be turned so as to direct the neck 15 upwardly, in which case water may be readily poured onto the sponge or the like, through the wide open mouth of the neck. The holder 14 is preferably spherical and composed of transparent material such as glass and the parts thereof are preferably integral therewith. The diameter of the holder 14 is preferably much less than the diameter of the base 10, and as the said holder is located at the top of the appliance when it is in use in smoking, it can easily be seen and observed by the smoker, the smoke passing through the sponge producing weird yet attractive effects.

The holder 14 is formed at points about half way of its neck and its apex with openings which are provided by nipples 19, 20 that extend diametrically of the holder, such nipples being exteriorly screw-threaded for receiving screw-threaded removable extension nipples 20, 21. These extension nipples may be of hard rubber. A coupling member 25 is provided, having a suitable head 22 with oppositely extending necks 23, 24, all preferably made in one piece of hard rubber. This coupling member is removable, its neck 23 being inserted with a friction fit into the extension nipple 21, and the coupling member being provided with a through passage which leads to the bowl or holder 25 of a tobacco pipe provided with a stem 26 having an enlarged bore 27 to receive the neck 24, whereby to removably couple the pipe with the coupling member. Preferably the holder 14 is considerably greater in diameter than that of the bowl 25 so that it has a spacious chamber which when filled with a wet sponge 18, for example, provides a very extensive surface at which the wired and attractive effects produced by the smoke are visible.

A second coupling member is also provided, comprising a suitable head 29 and oppositely extending necks 30, 31, the neck 30 being inserted with a friction fit into the extension nipple 20, whereby to removably secure the said coupling member to said nipple. The coupling member 29, 30, 31 is also provided with a through passage, and tightly into the neck 31 there is inserted one end of a length of flexible tubing 32. To the other end of the tubing 32 there is attached a suitable mouth-piece 33, for enabling the tobacco in the bowl 25 to be smoked.

It will be seen that the parts of the smoking appliance may be detached from each other for convenient shipment or storing away in compact condition and that the parts may be readily reassembled for use.

What I claim, is:

1. A tobacco smoking appliance, comprising a holder for absorbent material, having a wide-mouthed, exteriorly screw-threaded, downwardly extending neck, a supporting

base having a shallow, cylindrical top recess with a screw-threaded wall to be engaged by the screw-threaded neck, a substantially flat packing disk secured between the lower end of the neck and the bottom of the recess and closing the neck, and a tobacco holder and a mouth-piece connected with the holder at opposite points thereof, said holder for absorbent material being considerably larger than the tobacco holder.

2. A tobacco smoking appliance, comprising a transparent holder for absorbent material, having an integral wide-mouthed open neck, and provided with integral nipples extending outwardly therefrom at diametrically opposite points, a supporting base, into the top of which the neck is threaded, a tobacco holder and a mouth-piece, and removable coupling means for connecting the tobacco holder and mouth-piece with the respective nipples, the interior diameter of the said nipples being greater than the passages through the coupling means.

3. A tobacco smoking appliance, comprising a transparent spherical holder for absorbent material, having an integral wide-mouthed open neck approaching the diameter of the holder, and permitting the ready insertion of the absorbent material, said holder provided with integral nipples extending horizontally outward at diametrically opposite points from the greater dimension of the holder, a relatively heavy supporting base of greater diameter than the spherical holder and into the top of which the neck is threaded, a tobacco holder and a mouth-piece, and removable coupling means for connecting the tobacco holder and mouth-piece with the respective nipples.

4. A tobacco smoking appliance, comprising a transparent, spherical holder for absorbent material, having a wide-mouthed neck approaching, but slightly less than, the diameter of the interior of the holder, a relatively heavy supporting base, with the top of which the neck is threaded, whereby the holder and absorbent material are positioned above the base, said base having means to enable it to rest on a level surface, the holder provided with diametrically opposite, horizontally disposed openings above the neck, means for connecting a tobacco holder with one opening, and means for connecting a mouth-piece with the other opening.
